MAGAZINE SHAVING BRUSH

Filed June 17, 1932

INVENTOR.
CHARLES C. WUEST
BY Adam E. Fisher

ATTORNEY.

UNITED STATES PATENT OFFICE

CHARLES C. WUEST, OF ST. LOUIS, MISSOURI

MAGAZINE SHAVING BRUSH

Application filed June 17, 1932. Serial No. 617,708.

This invention relates to shaving brushes of the magazine or reservoir type, and the principal object of the invention is to provide in a simple and practical form a shaving brush having a reservoir within which individual cartridges of shaving cream may be deposited as desired, with means for forcing same outwardly into the brush as required in use.

Another object is to provide a shaving brush having a reservoir for the reception of a cartridge of shaving cream, the said cartridge being formed with a screw spiral groove upon its inner cylindrical walls, with means for locking the cartridge against rotation within the reservoir and additional means for forcing the cream from the cartridge out into the brush as required for use.

With these and such other objects and advantages in view as may be developed in the following specification, attention is now directed to the accompanying drawing as exemplifying a preferred embodiment of my invention and wherein

Figure 1 is an elevation of a shaving brush constructed in accordance with my invention;

Figure 2 is a longitudinal section through the brush as shown in Figure 1;

Figure 3 is a transverse section on the line 3-3 of Figure 2.

Figure 4 is a detail view of a cream cartridge as contemplated in the practise of this invention, the inner screw spiral groove thereof being shown in dotted lines.

Figure 5 is a bottom end view of the said cartridge.

Figure 6 is a fragmental sectional detail of a modification of the form of plunger assembly shown in Figure 2.

Figure 7 is a plan view of the plunger disc as represented in Figure 6.

In carrying out this invention, I provide a shaving brush designated generally at 1, the same comprising a tubular or cylindrical form of handle 2 closed at one end 3 and open at the other end 4, there being apertures 5 formed through the closed end leading out into the bristles 6 constituting the brush proper. The tubular handle referred to thus pro-

vides a magazine or reservoir 7 for the reception of a cartridge 8 of shaving cream, the cream being indicated at 9. In accordance with my invention, it is contemplated that the cartridge 8 be made of some suitably cheap substance such as press-board, mill-board, the same being pressed or formed into the cylindrical shape represented in the drawing and having also formed upon its inner walls from end to end the screw or spiral groove 10. The cartridge 8 is left open at its ends in the making, and is filled with the shaving cream and then sealed at the ends with a wafer 11 of wax, gummed paper, or any other suitable material for the purpose. The cartridge 8 is formed so as to snugly fit within the said reservoir 7 and is anchored against rotation therein by means of recesses 12 formed diametrically opposite in the outer peripheral margin of the end of the cartridge and adapted to engage registering lugs 13 formed in diametrically opposite relation at the inner end of the reservoir 7. A tubular extension or cap 14 is provided, the same being adapted to snugly telescope over the said handle 2, and the outer end thereof being closed as shown at 15. From this closed outer end a plunger rod 16 is extended axially within the extension 14, and a plunger 17 is rigidly mounted at the free end of the said rod, the said plunger being provided with a screw or spiral thread 18 for engaging the said groove 10 of the cartridge 8.

In the use of the assembly as described, the cartridge 8 loaded with shaving cream is inserted within the magazine or reservoir 7 of the handle, the end sealing wafers 11 being first removed. The cap 14 is then positioned at the end of the handle, the plunger 17 is entered at the open end of the cartridge and placed in engagement with the spiral groove 10. A turn or two upon the cap 14 then serves to force cream out through the apertures 5 into the bristles 6, ready for use. When the cream is exhausted from one cartridge, the empty shell may be readily removed and another loaded cartridge inserted. In the modification shown in Figures 6 and 7, one end of the cartridge is sealed with a heavy disc 19 of mill-board or the like, the same

having a center slot 20 for the reception of the complementary, flattened end 21 of the plunger rod 16, thereby dispensing with the permanent plunger 17 of the previously described assembly. The disc is also provided with a thread 18 for the groove 10.

While I have herein described a certain specific manner and method of constructing and assembling the elements of my invention, 10 it is understood that I may vary from the same in minor details, not departing from the spirit of my invention, so as best to construct a practical device for the purpose intended, as defined in the appended claims.

15 I claim:

1. In a device of the kind described, the combination of a tubular handle open at one end, a tubular cartridge removably seated within the handle, the same having a screw groove formed upon its inner walls from end to end, a tubular cap telescopically mounted over the open end of the handle, the outer end of the cap being closed, a plunger rod extended axially within the cap from the closed end 20 thereof, and a plunger rigidly mounted at the free end of the rod, the plunger having a screw thread complementary to the screw groove of the cartridge.

2. In a device of the kind described, the combination of a tubular handle open at one end, a tubular cartridge frictionally seated within the handle, the cartridge having a screw groove formed upon its inner cylindrical surface, a tubular cap telescopically mounted over the open end of the handle and frictionally engaging the outer cylindrical surface thereof, the outer end of the cap being closed, a plunger rod extended axially within the cap from the closed end thereof, and a plunger 35 rigidly mounted at the free end of the rod and provided with a screw thread for engaging the screw groove of the cartridge.

3. In a device of the kind described, the combination of a tubular handle with at least 40 one end open, a tubular cartridge removably seated within the handle, a tubular cap removably and telescopically mounted over the open end of the handle and adapted to frictionally engage the outer cylindrical surface 45 thereof, the outer end of the cap being closed, a plunger rod extended axially within the cap from the closed end thereof, and a plunger rigidly mounted at the free end of the rod and adapted to move within the handle.

50 55 In testimony whereof, I affix my signature.
CHARLES C. WUEST.
